LIQUID FUEL CONTROL SYSTEM

Original Filed July 5, 1919

INVENTOR
Sidney G. Down
BY *John M. Brady*
ATTORNEY

UNITED STATES PATENT OFFICE.

SIDNEY G. DOWN, OF BERKELEY, CALIFORNIA, ASSIGNOR TO ASSOCIATED ENGINEERING AND SUPPLY COMPANY, OF SAN FRANCISCO, CALIFORNIA, A CORPORATION OF CALIFORNIA

LIQUID-FUEL-CONTROL SYSTEM.

Original application filed July 5, 1919, Serial No. 308,886. Divided and this application filed December 18, 1920. Serial No. 431,769.

To all whom it may concern:

Be it known that I, SIDNEY G. Down, a citizen of the United States, residing at Berkeley, in the county of Alameda and State of California, have invented new and useful Improvements in Liquid-Fuel-Control Systems, of which the following is a specification.

This invention relates to a steam boiler stoking apparatus having means for automatically regulating the intensity of the fire and the furnace draft, the present application being a division of my pending application, Serial No. 308,886, filed July 5, 1919, and issued as Patent No. 1,375,492, dated April 19, 1921.

The present divisional application involves more particularly that feature of the invention in which variations in the forced draft effect the operation of devices for regulating the intensity of the fire, including the regulation of the draft and the supply of fuel.

Other objects and advantages will appear in the following more detailed description of the invention.

In the accompanying drawing, Fig. 1 is a diagrammatic side elevational view, partly in section, of a liquid fuel burning system embodying my invention; Fig. 2 an end elevation thereof; and Fig. 3 an enlarged sectional view of the fuel controlling device.

As shown in the drawing, the apparatus may comprise a steam boiler 1 having a furnace door opening 2 and a smoke stack 3. For regulating the flow of liquid fuel a controlling device 4 is provided which is adapted to operate a shaft 5 to which is operatively connected a stack damper 6, a valve 7 in the pipe 8 for controlling the flow of fuel oil to the furnace, and an ash pit door 9.

In order to atomize the liquid fuel I provide an electric motor 10, to the shaft 11 of which is attached a conical disk 12, the mounting being such that the disk 12 is positioned within the furnace, adjacent to the furnace door opening 2.

The liquid fuel supply pipe 8 leads into the conical disk, so that as the liquid fuel flows from the pipe into the disk, it is atomized and sprayed into the furnace by centrifugal action due to the rapid revolution of the motor shaft 11.

The speed of the motor 10 is controlled by

a rheostat 42, the contact arm 13 of which is 55 operatively connected through a rod 14 and a lever 15 with the shaft 5.

The controller 4 may comprise a casing having piston chambers 16 and 17 containing the respective pistons 18 and 19. The piston stems 20 and 21 of the respective pistons 18 and 19 are pivotally connected to a cross head 22 which in turn is pivotally connected to a rod 23, and the rod 23 is connected to a lever 24, secured to the shaft 5.

The space at the under side of each piston is connected by pipe 25 to an oil supply pipe 60 which leads to a constant source of fluid pressure, preferably utilizing the pressure of the liquid employed as fuel, as shown in 70 the drawing.

The pistons 18 and 19 are provided with the respective equalizing ports 26 and 27 through which the fluid under pressure below each piston tends to equalize into the 75 space above the corresponding piston.

Valves 28 and 29 having corresponding valve stems 30 and 31 are provided for effecting the exhaust of fluid under pressure above the respective pistons 18 and 19 to a 80 pipe 32.

The valves 28 and 29 are yieldingly held seated by the respective springs 33 and 34 and for effecting the opening of the valves, a cross head 35 is provided, having adjustable 85 hand screws 36 and 37 adapted to engage the respective valves 28 and 29.

The cross head 35 is connected by a stem 38 with a flexible diaphragm 39, subject on one side to the pressure of an adjustable coil 90 spring 40, and on the opposite side to steam pressure, as supplied through pipe 41 from the steam boiler 1.

The stack damper 6 is connected by an arm 43, rod 44 and lever 45 with shaft 5, 95 while the valve 7 is connected to said shaft through arm 46, rod 47, and lever 48. The ash pit door 9 may be operated by a chain 49 adapted to engage a sheave 50 on the shaft 5.

A weighted arm 51 is connected to the shaft 5 and tends to rotate the shaft by gravity.

In operation, if the steam pressure in the boiler exceeds a predetermined maximum degree, the force of the spring 40 of the controller 4 will be overcome by steam pressure acting on the diaphragm 39 so that the

diaphragm will move the rod 38 to its lowest position, in which the screws 36 and 37 engage both valves 28 and 29 and open same.

5 Liquid fuel under pressure, previously equalized into the chambers above the pistons 18 and 19 through the ports 26 and 27, is then exhausted through pipe 32, so that said pistons are shifted to their uppermost 10 positions by the pressure of liquid acting below the pistons.

The rod 23 is then raised by the pistons 18 and 19 so as to effect the partial rotation of shaft 5 to the position shown in Fig. 1 of 15 the drawing.

In this position, the valve 7 is closed to a predetermined extent so as to provide the desired rate of flow of liquid fuel for a minimum fire. The rheostat arm 13 is in 20 position for cutting resistance into the circuit of the motor 10 so that said motor rotates the shaft 11 and the conical disk 12 at a minimum speed.

The liquid fuel flowing through pipe 8 to 25 the disk 12 is then thrown out by centrifugal force and is atomized and sprayed into the furnace.

In this position, the rod 44 operates the stack damper 6 so as to restrict the draft to 30 correspond with the restricted fire and the ash pit door 9 is also moved to restrict the draft through the ash pit.

It may here be stated that the screws 36 and 37 are so adjusted that the screw 37 is 35 nearer the valve stem 31 than the screw 36 to the valve stem 30, as shown in Fig. 3 of the drawing, with the result that when the diaphragm 39 moves the cross head 35 downwardly, the screw 37 will engage the valve stem 31 and open the valve 29 before the screw 36 engages the valve stem 30 to open the valve 28. On the upward movement of 40 the diaphragm 39, the movement of the cross head 35 will cause the screw 36 to move 45 away from the valve stem 30 before the screw 37 moves away from the valve stem 31, so that the valve 28 will close first during the upward movement of the diaphragm.

If the steam pressure in the boiler reduces 50 to a predetermined degree, the pressure of the spring 40 will move the diaphragm 39 against the reduced steam pressure, so as to move the cross head 35 upwardly and first permit the valve 28 to close while the valve 55 29 remains open. The liquid pressure on the under side of the piston 18 will then equalize through the restricted port 26 permitting the piston 18 to move down and thereby rotate the shaft 5 through the rod 60 23 and the lever 24.

The rotation of shaft 5 causes the valve 7 to be opened wider, so that an increased flow of liquid fuel is supplied to the disk 12 while the rheostat arm 13 is moved to 65 cut resistance out of the circuit of the mo-

tor 10, so that the motor will speed up to correspond with the increased flow of liquid fuel.

The stack damper 6 and the ash pit door 9 are also moved to provide an increased 70 draft in accordance with the requirements of the increased furnace fire.

If the steam pressure in the boiler continues to fall, the spring 40 will move the diaphragm 39 and rod 38, so as to permit 75 the closing of valve 29 and the consequent equalization of pressures on opposite sides of the piston 19.

The piston 19 then moves downwardly and causes the further rotation of shaft 5, so 80 that the valve 7 is opened still wider, while the rheostat arm 13 is again shifted to cut out more resistance from the motor circuit and thus permit the further speeding up of 85 the motor 10.

As will be evident, the stack damper 6 and the ash pit door 9 are also operated to provide a further increase in the draft openings.

When the steam pressure rises above a 90 predetermined degree, the diaphragm 39 is depressed by the increased steam pressure so as to shift the cross head 35 downwardly to first open the valve 29 while the valve 28 remains closed. Liquid under pressure is 95 then vented from the chamber above piston 19, so that said piston is operated by the liquid under pressure below the piston and the rod 23 operates to rotate the shaft 5, so that the stack damper 6 and the ash pit 100 door 9 are partly closed, while the valve 7 is operated to reduce the flow of liquid fuel through pipe 8 and the speed of the motor 10 is reduced by the operation of the rheostat arm 13 to cut resistance into the motor 105 circuit.

If the steam pressure rises still further, the diaphragm 39 is moved further by steam pressure so as to cause the cross head 35 to operate the valve 28 and vent liquid 110 from the top of piston 18. Said piston then lifts the rod 23 and rotates the shaft 5 a further amount, so that the speed of the motor and the flow of liquid fuel is further reduced, while the stack damper 6 and the ash 115 pit door 9 are further closed, to reduce the draft to correspond with the reduced fire.

The construction as so far described constitutes the subject matter upon which the claims in my pending application, herein- 120 before referred to, are based, and I will now describe the construction and operation with respect to control by variations in forced draft and relating more specifically to the subject matter claimed in the present divisional application.

If forced draft be employed, means may be provided for operating the controller 4 according to variations in the degree of 125 forced draft.

For this purpose, an auxiliary valve device 51 is provided, comprising a casing containing a diaphragm 52, subject on one side to a spring 53 and having a stem 54 for operating a valve 55 adapted to control the venting of liquid from the piston chamber 17 of the controller 4. The chamber above the diaphragm is connected by a pipe 56 to the interior of the usual steam nozzle 57, which is mounted in the smoke stack 3 for producing forced draft.

In operation, if the forced draft is operating, the pressure of steam in the nozzle 57 acts on the diaphragm 52, against the resistance of spring 53 to hold the valve 55 closed, so that the controller then operates as hereinbefore described.

If, however, the forced draft is shut off, then the pressure above the diaphragm 52 will be reduced, enabling the spring 53 to operate the diaphragm to open the valve 55 and vent liquid above piston 19 to the exhaust.

The piston 19 will then be lifted by the liquid pressure acting below the piston, so as to rotate the shaft 5 to a position for reducing the intensity of the fire.

Having now described my invention, what I claim as new and desire to secure by Letters Patent, is:—

1. In a steam boiler stoking apparatus, the combination with a steam boiler, of means for controlling the supply of fuel to the boiler furnace, a piston operatively connected to said means and responsive to a differential of pressures on its opposite sides for operating said means, a valve for establishing a differential of pressures on said piston, a diaphragm subject to variations in steam boiler pressure for operating said valve, and a valve device operated by variations in pressure of exhaust steam from an engine operated by steam from the boiler for also creating a differential pressure on said piston.

2. In a steam boiler stoking apparatus, the combination with a steam boiler, of means for regulating the atomizing of liq-

uid fuel supplied to the boiler furnace, a piston operatively connected to said means and responsive to a differential of pressures on its opposite sides for operating said means, a controlling device subject to variations in steam boiler pressure for establishing a differential of pressures on said piston, and a valve device operated by variations in pressure of exhaust steam from an engine operated by steam from the boiler for also creating a differential pressure on said piston.

3. In a steam boiler stoking apparatus, the combination with a steam boiler, of means for regulating the furnace draft a piston operatively connected to said means and responsive to a differential of pressures on its opposite sides for operating said means, a main controlling device subject to variations in steam boiler pressure for establishing a differential of pressures on said piston, and an auxiliary valve device subject to variations in the pressure of exhaust steam from an engine operated by steam from the boiler for also creating a differential pressure on said piston.

4. In a steam boiler stoking apparatus, the combination with a steam boiler, of mechanism for regulating the supply of liquid fuel to the boiler furnace, for regulating the atomizing of the liquid fuel, and for regulating the furnace draft, a piston operatively connected to said mechanism and responsive to a differential of pressures on its opposite sides for operating said mechanism, a main controlling device subject to variations in steam boiler pressure for establishing a differential of pressures on said piston, and an auxiliary valve device subject to the variations in the pressure of the exhaust steam from an engine operated by steam from the boiler for also creating a differential pressure on said piston.

In testimony whereof I have hereunto set my hand.

SIDNEY G. DOWN.
